UNITED STATES PATENT OFFICE.

JOHN BRICKEN, OF CHICAGO, ILLINOIS, ASSIGNOR TO THE WAHL COMPANY, OF WILMINGTON, DELAWARE, A CORPORATION OF DELAWARE.

CALCULATING-MACHINE.

1,266,660.

Specification of Letters Patent. Patented May 21, 1918.

Application filed March 24, 1914, Serial No. 826,833. Renewed October 6, 1916. Serial No. 124,204.

To all whom it may concern:

Be it known that I, JOHN BRICKEN, a subject of the Emperor of Russia, residing at Chicago, in the county of Cook and State of Illinois, have invented a certain new and useful Improvement in Calculating-Machines, of which the following is a specification.

My invention relates to calculating machines, particularly those which are associated with typewriters. A good example of this class of machine in fact the machine on which I show an application of my present invention, is shown and described in the patent issued to John C. Wahl, #893,719, dated July 21st, 1908.

One of the objects of my invention herein described is the automatic printing of totals *seriatim*, that is, automatically printing a total digit by digit in distinction to the usual method employed in adding machines of printing all of the digits of a total simultaneously.

Another object of my invention is the automatic printing of a total present in a calculating machine of the type described in the aforementioned patent to Wahl. These and further objects of my invention will be disclosed and referred to hereinafter in the following specification and claims.

I have shown my invention on a typewriting calculating machine of the class shown in the cited patent to Wahl.

Referring to the figures illustrating my invention

Figure 1 is a section on line 1—1 of Fig. 2, Fig. 2 is a front view of a typewriter and calculating machine,

Fig. 3 is a section on line 3—3 of Fig. 1,

Fig. 4 is a section on 4—4 of Fig. 3,

Fig. 5 is a section on line 5—5 of Fig. 1 partly in plan,

Fig. 6 is a section on line 6—6 of Fig. 2,

Fig. 7 is a section on line 7—7 of Fig. 6,

Fig. 8 is a view along the line 8—8 of

Fig. 6,

Fig. 9 shows some of the mechanism shown in Fig. 1, in its alternative position,

Fig. 10 is a perspective view of certain mechanism coöperating with the totalizer and automatic key operating device of my present invention,

Fig. 11 is a view of one of the carrying gears of the totalizer showing the three short teeth, and

Fig. 12 is a view of the totalizer from the right showing the relation of the totalizer side plates to the carrying gear in the lowest decimal place thereon.

Before entering into a detailed description of my invention, I shall give a general outline of the theory of its operation.

The calculating machine is provided with a totalizer which is adapted to receive numbers *seriatim* as these numbers may be set up on the digit keys. This part of the mechanism is substantially similar to that shown in the cited patent to Wahl. The totalizer has in each decimal place thereof a movable part whose displacement from the zero position represents the number in said decimal place. Coöperating with the totalizer is a single set of feelers. These are thrown into contact with the movable member of the totalizer at the proper time and as a result of such engagement one of the feelers is displaced. These feelers control a set of latches, each connected to a digit key of the typewriter, including the zero key, and the latch corresponding to the displaced feeler is thrown into engagement with a vibrating bar driven by a source of power such as an electric motor or other suitable means. As the said bar vibrates it will engage with the particular latch which has been displaced and thereby operate the digit key of the typewriter. This operation will produce precisely the same effect as if the key were operated by hand. The typewriter carriage will escape so that the set of feelers before referred to will be in line with the next lower decimal place of the totalizer. The set of feelers will again be thrown into coöperation with the totalizer, and a latch corresponding to the digit in that decimal place of the totalizer thrown into the path of the vibrating bar. A second key will then be operated by said bar, thus printing the second digit of the total. This operation will be repeated for each decimal place of the totalizer until the entire number appearing in the totalizer has been printed. A lever determining that the totalizer shall be operated in subtraction is supposed to have been set before the beginning of the automatic extraction of the total. Consequently during the operation, the totalizer will be cleared. When the digit in the last decimal place has been printed, the automatic total

printing mechanism will be stopped, thus calling the operator's attention to the fact that the total existing on the machine has been printed. Then the machine is ready for further calculation.

Owing to the complex nature of my machine, I shall first describe each section separately and subsequently describe the co-operation of the various portions of the machine.

The totalizer and actuating mechanism.

The totalizer and actuating mechanism are substantially like those shown in the cited patent to Wahl. A set of digit keys 130 to 139 are mounted in a typewriter 16, and co-operate with the usual printing mechanism 17, which is adapted to print numbers on a platen. The typewriter with which the calculating machine is shown is the well known Remington typewriter, which will be recognized from the outlines in Figs. 1 and 2. Each of the digit keys 130 to 139 inclusive is connected by a pull rod 19 to a fan 20 in the actuator. These fans of which there is one to each digit key, are rotatably mounted on a shaft 21, rigid in the frame work 22 of the machine. There is provided a master wheel 23, and master dog 24, both of which are moved in consequence of the operation of any digit key 130 to 139 in the manner described in the cited patent to Wahl, viz., the master wheel is rotated a number of steps depending upon the particular key operated, and prior to such rotation, the master dog is rotated on its axis in a counter clockwise direction, (Fig. 6) thus unlocking the chain of totalizer gears at the actuated point.

The totalizer is mounted on a truck 26 which moves step by step with the typewriter carriage as the latter escapes due to the operation of the digit keys. Numbers are thereby inserted into this totalizer by the master wheel *seriatim*, beginning with the digit in the highest decimal place and progressing to the lowest as the totalizer escapes step by step upon the operation of the keys.

The totalizer 25 is substantially like that shown in the cited patent to Wahl. In it is provided a set of carrying gears 26 provided with carrying teeth 27, and these gears are rotatably mounted on a shaft 28 rigid in the frame work of the totalizer. A set of transfer gears 29, mounted on a set of swinging arms 30 serve to transfer the tens at the proper time. These transfer gears 29 and the carrying gears 26 form normally a locked gear chain, which is unlocked at the actuated point by the master dog 24 lifting a swinging arm 30 prior to the rotation of the master wheel 23. The direction of rotation of the master wheel

may be determined by the position of the subtraction lever 31 which lever corresponds in position and function to the lever 62 in the cited patent to Wahl. So far the construction of my machine is substantially that of the machine shown in the aforementioned patent, but from this point, my machine begins to differentiate therefrom.

Reference to Figs. 6 and 11 will show that the carrying gears 26 having thirty teeth and three carrying teeth 27, are provided with three short teeth. These teeth are not wholly cut away, but have simply the points removed, and their action with the transfer gears 29 and the idle gears 32, serving to transmit the motion of said carrying gears to the number disks 33, is substantially the same as if the points of the teeth were present. The number disk 33 of any decimal place and the carrying gears 26 associated therewith are so meshed together that when a short tooth is in the position shown in Fig. 6, the number wheel associated with said wheel is in a position to exhibit the 0 through the window 34 in the casing 35 of the totalizer. In Fig. 6, I have placed a small 0 opposite this position of the short tooth and shall refer to such position as the 0 position.

It is to be noted that in the Wahl totalizer there are two sets of transfer gears 29, a gear of each set being placed on alternate arms 30 as disclosed in the cited patent to Wahl. This staggered construction makes it necessary to have two species of carrying gears 26 in my present invention, these species being different in the relation of the short teeth to the carrying teeth 27 of said gears, the arrangement being such that when the carrying teeth of all the carrying gears 26 are in contact in the same direction with their associated transfer pinions 29, one of the short teeth on each carrying gear 26 will be in a position corresponding to the 0 position of said gear.

The feelers and latches connected therewith.

In the same vertical plane as the master wheel 23 is a set of feelers which I have numbered 40 to 49 inclusive. These feelers are rotatably mounted on three shafts 155, 156 and 157, rigid in the frame work, and are connected by a set of links 50 to 59 inclusive to projecting arms rigid on a set of rock shafts 60 to 69 inclusive fulcrumed in the frame work. Each of these rock shafts has a depending arm which I have numbered 70 to 79, inclusive, rigidly attached thereto. Each of these depending arms 70 to 79 has pivoted at its lower end a link numbered 80 to 89 inclusive to correspond to the arms to which said links are attached. Each digit key has pivoted thereon a latch. These latches I have numbered 90 to 99 inclusive, the digit in the

units place of the reference number of these latches corresponding to the digit key to which said latch is attached. For instance, latch 90 is attached to the 0 key. Latch 91 is attached to the 1 key and so on. The chain of mechanism from the carrying gear 26 up to and including the latch 90 is best shown in the perspective view of Fig. 10.

Each latch has in it a pin 100, which operates with a fork 101 in the end of its associated link 80 to 89. A set of tension springs 102 connects each of the latches 90 to 99 to its associated link 80 to 89. A set of springs 103 serve to hold the depending arms 70 to 79 in a position determined by a universal rod 104 which rod contacts with all of the depending arms 70 to 79.

At this point, it should be noted that the feeler 40 for instance is connected to the rock shaft 60 by the link 50 and on the rock shaft 60 is mounted the depending arm 70, which is connected by the link 80 to the latch 90, mounted on the 0 digit key. Similarly the feeler 41 is connected by the link 51 to the rock shaft 61 on which is mounted the depending arm 71, controlling the link 81 associated with the latch 91 on the 1 digit key. This same system of reference numbers has been followed for all of the other digit keys so that the digits in the units place of the numbers 50 to 99 both inclusive, will identify the particular digit with which such numbered part is associated.

Reference to Fig. 6, in which is shown a plan view of the carrying gears 26 in the lowest decimal place, shows that the position of the short tooth on said wheel is determined by the position of the number disk 33 in mesh with said wheel. The feeler 40 is opposite this 0 position of the short tooth. The feeler 41 is opposite the position immediately above the 0 position. The feeler 42 is opposite the next succeeding position. The feeler 43 is at the extreme lower part, and this feeler will contact with the short tooth belonging to the next cycle of ten teeth. The feelers 44, 45, 46, 47, 48 and 49 respectively, follow in the order given. An inspection of Fig. 6 will then clearly show that if the entire bank of 10 feelers is allowed to come into contact with the carrying gear 26, the feeler which is opposite the short tooth will enter the wheel deeper than the others, and that this additional displacement will result in a displacement of the latch associated with said feeler relative to the other 9 latches. The particular feeler which is thus displaced upon such engagement of the feelers with the gears 26 depends upon the position of the short tooth, and since, as has been before explained, the short tooth has a definite relation to the number disk 33 geared to the carrying gear 26, motion of all the feelers into mesh with said wheel will result in the displacement of

a particular latch and this latch will correspond to the number exhibited by the number disk 33.

It will be remembered that each of the latches numbered 90 to 99 inclusive is associated with the particular digit key corresponding to the digit in the units place of the designated number of the latch. Therefore upon engaging all of the feelers with any carrying gear 26, the latch associated with the digit key corresponding to the position of said gear will be displaced in advance of the other 9 latches. It is by means of this displacement that I am able to select the particular digit key which is to be operated.

Mechanism for engaging the feelers 40 to 49, inclusive, with the carrying gears 26 of the totalizer.

I have mentioned in the preceding division of this specification the universal rod 104. This rod is shown perhaps most clearly in Fig. 10. It is also shown in Figs. 1 and 6. This rod 104 is supported on two arms 105, rigid on a shaft 106, pivoted in the frame work of the machine. At suitable times during the operation of the machine, the shaft 106 is rocked in a clockwise direction, Fig. 10, thereby withdrawing the universal rod 104 from the path of the depending arms 70 to 79. This allows these arms to rotate in a counter clockwise direction (Fig. 10) under the influence of their respective springs 103, and through the linkage connecting said depending arms to the feelers 40 to 49, and bring all of said feelers in contact with the particular carrying gear 26 which may be in the plane of said feelers at that time.

Source of power for operating the keys.

In the previous description, I have followed the mechanism through to the point where a latch associated with a particular digit key is displaced relative to the other latches to thereby determine what particular key shall be operated. I shall now describe the source of power for operating the keys following the displacement of said latch.

Attached to the frame work 22 of the typewriter, I have shown a suitable source of power, which in my application is a continuously running electric motor 108. Of course any other suitable source of power, such as a continuously rotating shaft driven by a belt might be used. A power shaft 107 is rotatably mounted in the frame work of the machine, and on this shaft is loosely mounted a pulley 109, connected to the motor 108 by a belt 110. Slidably but non-rotatably mounted on the shaft 107 is a clutch 112, (best shown in Fig. 2) controlled by a handle 111. The clutch consists of the usual two engaging members, one of

which is shifted by the handle 111, and I shall not at this place enter into a detailed description of it since there are many suitable clutches in the prior art, any one of which would answer the purpose of the particular form shown here. All that is necessary is that there be some means of connecting the pulley 109 to the power shaft 107.

Rigidly mounted on the power shaft 107 is an arm 113, on which is pivoted a pawl 114, which is held in engagement by a spring 115 to the disk 116 loosely mounted on the shaft 107. The disk 116 has a series of notches 117 into which the pawl 114 engages thereby transmitting the rotation of the power shaft 107 to the disk 116. In case the disk 116 should be at any time prevented from rotating the pawl 114 will ride out of the notches 115 and the shaft 107 may still rotate notwithstanding the fact that rotation of the disk 116 is prevented. The object of this slip clutch will be afterward explained.

Projecting from the disk 116 is a crank pin 118 on which is mounted a link 120 pivoted to an arm 121, rigid to a shaft 122, rotatably mounted in the frame work. This linkage just described consists of the crank pin 118 on the disk 116 which in effect forms a crank arm on the shaft 107; the link 120 and the arm 121 form a well-known linkage serving to oscillate the arm 121 upon rotation of the shaft 107. Rigidly attached to the shaft 122 are a pair of arms 123, located at either end of said shaft, and these arms have mounted between them a rod 124 which serves to operate the latches 90 to 99 inclusive. From the preceding it is apparent that rotation of the power shaft in case the clutch 112 is thrown in the position shown in Fig. 2, will result in a vertical oscillation of the rod 124, and in case any latch is in position to engage said rod 124 on the downward motion of the same, the digit key connected to said latch will be operated.

I shall now describe the means by which the vertical oscillation of the rod 124 results in operation of the typewriter digit keys. Referring especially to Figs. 1 and 9, it will be noted that the latches 90 to 99 inclusive have formed in them at their upper ends, a recess 125. Since all the latches 90 to 99 inclusive, are similar in shape and have the same action with the rod 124, I have numbered the latch shown in Fig. 9 as 90, and the following remarks will apply to any of the other nine latches of the set. Inspection of Fig. 9 will show that if when the rod 124 is in its uppermost position, the latch 90 be allowed to move from its dotted position to its full position, when the rod 124 descends said rod will engage the lower portion of the recess 125, depress the latch 90 and consequently the 0 digit key 130 to

which the latch 90 is connected will be depressed.

I shall now describe the means for bringing the latches into position to engage the rod 124. On the arm 121 is a pin 126 which engages a link 127 pivoted to one of the arms 105. A spring 119 connected to the arm 105 serves to hold said arm in a normal position determined by the contact of the universal rod 104 with the depending arms 70 to 79, which in their turn are held in a normal position by the stay rod 128, rigid in the frame work. It is to be noted that the spring 119 is stronger than all of the springs 103 combined, so that said spring 119 always holds the depending arms 70 to 79 in contact with the stay rod 128 until such time as the universal rod 104 is removed by the action of the pin 126 on the link 127.

During the rotation of the crank pin 118 and consequent oscillation of the arm 121 and rod 124, the pin 126 will withdraw the universal rod 104 from the path of the depending arms 70 to 79. The associated springs 103 will therefore through the action of the mechanism connecting these depending arms to the set of feelers, throw all the feelers 40 to 49 against the particular carrying gear 26, which happens to be in the same plane as the feelers. According to the position of one of the short teeth on said wheel, the feeler contacting with such short tooth will enter deeper than the balance and the particular latch associated with such feeler will move from the dotted line position shown in Fig. 9 to the full line position. At the time of the withdrawal of the universal rod 104, the rod 124 is in its uppermost position. Consequently any latch is free to move into the position shown in full lines in Fig. 9.

Continued rotation of the crank pin 118 results in a depressing of the rod 124 and the particular latch which is in engagement therewith. It also results in the restoring of the universal rod 104 to its normal position and consequent disengagement of the nine non-actuated latches from the carrying gears 26. All of the latches then move to their normal position except the one which is in engagement with the rod 124. It is to be noted (Figs. 9 and 10) that the recess 125 has a projecting nose 129, which prevents the disengagement of the latch in contact with the rod 124 by reason of the tension of the spring 102. Consequently such latch is not returned to its normal position when the rod 104 returns to its normal position, but is carried down with the rod 124 as the latter descends, owing to the continued rotation of the crank pin 118.

The downward motion of the latch just described actuates the typewriter key to which said latch is pivoted, and the action of the typewriter is precisely the same as if said key were actuated manually. When the

key reaches its bottom position, the escapement of the typewriter is actuated, and the carriage escapes to its next decimal place, the feelers, of course, at that time being held out of engagement with the totalizer gears by the universal rod 104. When the rod 124 has reached its bottom position it will, of course, make a slight pause while the crank pin 118 is going over the dead center, but the digit key and the type bar connected therewith still have velocity at this point, consequently, the downward motion of the digit key will persist due to its momentum, and the projecting nose 129 will drop below the position of the rod 124. The latch will then be snapped back to its normal position relative to the link 80 by tension of the spring 102. After the crank pin 118 passes over the dead center, the rod 124 will start to rise. It will encounter a projecting lug 140 on the latch which was engaged therewith. Each of the latches 90 to 99 has these lugs 140 on its upper portion, and the function of this lug is to insure the digit keys being restored to its normal position before the rod 124 again descends. Each of the digit keys 130 to 139 has a restoring spring 141 tensioned between said key and the frame work, which spring tends to hold the digit key in its normal position. In case the digit key does not return to its normal position after having been operated by the rod 124, as fast as the rod 124 moves upwardly, the lug 140 serves to restore the digit key to its normal position upon the return movement of the said rod.

The operation of the machine.

I have described in detail most of the mechanism necessary to carry out my invention. I will now describe the operation of the same, taking as an example a definite number in the totalizer, and following the operation of the machine step by step during the automatic printing of such a number.

Assume that the totalizer has a capacity of 999 999 99 and that the reading on the totalizer as a result of the previous calculation is 654 30 and that it is wished to print out this number automatically by operating the digit keys *seriatim*. We will also assume that the handle 111 is in its "off" position, thereby disconnecting the oscillating rod 124 from the motor 108, and that the subtraction lever 31 is in the position determining that the machine shall operate in addition. The operation of the device will be as follows:

60 The operator first tabulates the carriage of the machine so that the master wheel engages the carrying gear 26 in the decimal place of the totalizer containing the first significant figure, viz., 6, and throws the subtraction lever 31 into its subtraction po-

sition. This being done, she throws the handle 111 into the "on" position. Neglecting for the moment the action of the universal cam 142, not previously referred to, operatively connected to the handle 111 by the link 143, the clutch 112 is engaged and the crank pin 118 starts to rotate thereby oscillating the rod 124. It is also assumed that the apparatus was started with the rod 124 in its uppermost position and it will be described hereinafter how the machine will always stop with the said rod 124 in this position. The first thing that happens after the clutch is engaged is the clockwise rotation of the rod 104 about its shaft 106, due to the action of the link 127, (Figs. 1 and 10). All the feelers then are thrown into engagement with the gear 26 of the totalizer by means of the springs 103 attached to the depending arms 70 to 79. The feeler 46 encounters the short tooth, and all the other feelers encounter long teeth. Consequently feeler 46 enters the wheel deeper than any of the others and through the intermediation of the connecting link 56, the rock shaft 66, the depending arm 76, the link 86, the latch 96 attached to the 6 key of the typewriter, is thrown in the path of the then descending rod 124. This position of the latch 96 would correspond to the full line position of the latch 90 shown in Fig. 9. Immediately after the latch 96 is engaged by the rod 124, the continued rotation of the crank pin 118 permits the universal rod 104 to rock about its shaft 106 under the tension of the spring 119 and thereby restores all of the depending arms and the feelers connected therewith to their normal position. It will be observed that the fork 101 in the end of the link 86 permits the restoring of the depending arm 76 in spite of the fact that the latch 96 is at that time engaged with the rod 124.

Continued rotation of the crank pin 118 depresses the rod 124 to its fullest extent, and as said crank pin is passing over the dead center, the continued downward motion of the 6 key prints a 6 on the platen, subtracts a 6 from the totalizer and un-hooks the latch 96 from the rod 124. During this downward stroke of the 6 key it contacts with a universal bar 144 extending under all of the typewriter keys, which bar is connected by a link 145 to the rock shaft 146 pivoted in the frame work of the machine. An arm 147 rigid with the rock shaft 146 is connected by a link 148 to the usual typewriter escapement mechanism 149. By means of the connections 144 to 149 just described, the typewriter carriage escapes. The upstroke of the rod 124 then follows. During the upstroke of the 6 digit key, the typewriter carriage escapes to a new position and the gear 26, which is five spaces angularly displaced from its 0

position is then in engagement with the master wheel and in the plane of the feelers.

As a result of the operations just described, a 6 has been printed on the work sheet and a 6 has been subtracted from the totalizer thereby restoring the gear 26 which was angularly displaced six spaces to its 0 position, and the carriage has escaped so that the master wheel is in engagement 70 with the gear 26 bearing the next digit of the total, viz., that displaced five spaces.

Continued rotation of the crank pin 118 again releases the feelers 40 to 49 by withdrawing the rod 104 out of the path of 15 the depending arms 70 to 79 and since the carrying gear 26 at that time in the plane of the feelers has an angular displacement of five spaces from the 0 position, the feeler 45 will contact with a short tooth, and as 0 described in the previous paragraph the latch 95 will be thrown into a position to engage the rod 124 upon the next descent of said rod. Continued rotation of the crank pin 118 permits the spring 119 to restore 5 the universal rod 104 to its normal position, thereby withdrawing the feelers from contact with the carrying gear 26. The rotation also results in a descent of the rod 124, carrying with it the latch 95 which is 10 in engagement therewith. As before described, the depression of this latch 95 results in the printing of a 5 on the work sheet, subtracting 5 from the totalizer and the escapement of the carriage one step. 35 The master wheel is now in engagement with the carrying gear 26, which is angularly displaced four spaces from its normal position and this gear is, of course, in the same plane as the feelers 40 to 49.

40 Continued rotation of the crank pin 118 now prints a 4 on the work sheet and restores the carrying gear 26 to its normal position as previously described, the only difference being that it is the latch 94 and the 45 digit key 134 which are actuated during this rotation of the crank pin 118. As a result of the printing of the 4, the carriage has escaped to the position where the master wheel is in engagement with the carrying gear 26 in a decimal or pointing off space of the totalizer. This case brings in a few new 50 considerations which will now be taken up.

When the totalizer is in a pointing off space, it is desirable to have no typewriter key operated at all since it is not wished to print anything in this space. The Wahl totalizers are usually made with the carrying gear 26 in a pointing off space rigid with the carrying gear of the next lower order 55 and the transfer gear 29 connecting these two gears 26 is of course omitted. In my present invention, the gear 26 in the decimal space has no short teeth. All of the teeth are of the full length. Consequently if the 60 feelers 46 be thrown against such a gear

none of them will be displaced and none of the latches 90 to 99 will be thrown into a position to be engaged by the rod 124. Therefore no typewriter key will be operated on the descent of the rod 124 when the totalizer stands in the pointing off space. However, it is necessary to have the carriage escape due to this oscillation of the rod 124. To this end, I have provided a projection 70 150 on the rock shaft 146 and have placed 75 the projection 151 rigid with the shaft 122 and in a suitable position to engage the projection 150 and operate the typewriter escapement independently of the universal bar 144.

The universal bar 144 is unnecessary to the operation of the typewriter escapement during the automatic printing of a digit. However, it must be remembered during the manual insertion of numbers by the digit 35 keys, the rod 124 is not oscillating, but is stationary, therefore the universal bar 144 is required to operate the typewriter escapement at that time. Its presence during the automatic operation of the digit keys does not interfere with the operation of the escapement by means of the lugs 150 and 151.

As a result of the oscillation of the rod 124 while the totalizer was in a pointing off space, nothing has been printed on the work 95 sheet, but the typewriter carriage has been escaped another step, and the master wheel is now in engagement with the carrying gear 26 which is displaced three spaces from its 0 position. Continued rotation of the 100 crank pin 118, as before, throws the feelers 40 to 49 into contact with this carrying gear 26, the feeler 43, by reason of encountering a short tooth, throws its associated latch 93 into a position to engage the rod 124 during 105 the descent of said rod. The feelers 40 to 49 are thrown out of contact with the carrying gear 26 by reason of the return of the universal rod 124 to its normal position, all 110 of the latches 90 to 99, with the exception of the latch 93 engaged with the rod 124, are restored to their normal position, and the descent of the rod 124 depresses the latch 43, and with it the digit key 133 to which 115 said latch is attached. The operation of the digit key 133 results in the printing of a 3 on the work sheet, restoring the carrying gear 26, which was angularly displaced three spaces, to its normal position, and the escape of the carriage to the last decimal place 120 of the totalizer.

When the feelers are thrown in a position to engage the carrying gear 26 in the lowest decimal place of the totalizer, the feeler 40 encounters the short tooth, consequently the 125 latch 90 is thrown into a position to engage the rod 124 on its descent, and the 0 key of the typewriter is operated. This results in the printing of the last digit of the total, viz., 0, and the operation is complete as far 130

as the printing of the total is concerned, so that there but now remains to describe how the mechanism is brought into its position of rest.

As a result of the operation of the 0 key, as described in the last paragraph, the totalizer escapes one other step and the feelers are now in the plane of the supporting side plate of the totalizer. The side plate 153 to the right of the gear 26 of lowest order is cut below the level of the short teeth of said gear (Fig. 12). Consequently when the feelers are thrown toward the totalizer due to the withdrawing of the universal rod 104, all of the latches 90 to 99 are thrown into a position to engage the rod 124. When the latter descends it consequently tries to operate all of the digit keys of the actuator at the same time. Since the Wahl actuator is provided with a single key mechanism, that is, a mechanism which prevents the operating of more than one digit key at any one time, the descent of the rod 124 is positively prevented by the said single key mechanism. Consequently the rotation of the crank pin 118 is prevented and the pawl 114 begins to slip over the notches 117 in the disk 116. This slippage results in a rattling noise, thereby notifying the operator, and calling her attention to the fact that the automatic printing of the total has been completed. The operator then throws the handle 111 to its "off" position, disconnecting the clutch and simultaneously operating the restorer cam 142.

In order to avoid complicating the description, I have, up to this point, omitted any description of the said restorer cam. It consists of a universal bar pivoted in the frame work and having a projection 152 adapted to contact with all the latches 90 to 99, (Figs. 1 and 10). When the bar is thrown into its dotted line position, shown in Fig. 1, all the latches 90 to 99 are held by the projection 152 out of the path of the rod 124. It will be remembered that this rod 124 was brought to rest in its uppermost position at the time the slip clutch connecting the crank pin 118 with the power shaft 107 began to yield, so consequently the parts are now in a position to automatically print a new total when the same has been accumulated in the totalizer by the manual operation of the digit keys 130 to 139.

Having now described the construction and operation of my improved machine, I wish to point out some of its advantages.

I consider the automatic printing of the totals *seriatim* by means of a source of power other than the manual operation of a handle or numeral keys a great advantage. It will be observed that in my present device, I have provided a source of power and means to connect said source of

power to the automatic total printing device, and automatically disconnect said source of power as an incident of the completion of the printing of said total.

I also wish to point out that I consider the particular mechanism comprising a single set of feelers adapted to coöperate with the totalizer in successive digit places of great advantage. By means of these feelers in connection with the device of providing the short teeth in the totalizer gears themselves, I am enabled to work directly from the totalizer without the addition thereto of locating mechanism such as separate cams and their associating gearing which would complicate the totalizer mechanism itself.

As an incidental advantage of the construction of the above mentioned machine, I call attention to the extreme simplicity of the device for taking care of the pointing off spaces. It will be observed that all that is necessary to take care of any number of pointing off spaces is to simply leave the teeth on the totalizer carrying gears in such spaces unaltered.

Attention is directed to the provision of the slip clutch consisting of parts 113 to 117 inclusive. This clutch, besides rendering the source of power operating the automatic total printing ineffective after the completion of a total printing operation, will also give an audible indication to the operator that the automatic printing of the total has been completed.

It is also to be noted that it is not at all necessary to the operation of my device that I subtract the total from the totalizer as an incident to the printing of said total. As is well-known, the Wahl machine is provided with a so-called "disconnect" handle, the object of which is to disconnect the actuator from the digit keys. If this handle is thrown to its "disconnect" position before starting the operation of printing a total, it is obvious that the totalizer gears will not be rotated at all during the printing of said total, and I am therefore enabled to print a total and leave the same unaltered in the totalizer, thus automatically printing out sub-totals during the course of a computation.

I do not wish to be confined in my invention to its application disclosed in this present specification, viz., to the calculating machine of Wahl's. It is obvious that the alphabetical printing features of the Wahl calculating machine are by no means necessary to the operation of my present invention, and that it may be used to advantage in non-alphabetical printing adding machines.

In typewriters like the Blickensderfer, for instance, the operation of the key levers determines the position of a wheel on which

the type are mounted and continued operation of one of these keys prints the selected character. Obviously my invention can be applied to a typewriter of this class instead of being applied to the type bar machine disclosed in this application. I consider the application of my invention to a machine printing by a wheel to be the equivalent of my present disclosure.

Many changes and variations may be made in the above described arrangement without departing from the spirit of my invention. I have illustrated it in its preferred form, but those skilled in the art will have no difficulty in adapting my invention to others than the Wahl machine. Therefore I do not wish to be limited to the precise arrangement and structure shown in this application since I claim:

1. In a calculating machine, the combination of a source of power, a totalizer, an automatic total printing device adapted to print *seriatim* the total in said totalizer, means coöperating with said totalizer to determine the number printed by said total printing device, and means to render said source of power inoperative on said total printing device upon the completion of the printing of said total.

2. In a calculating machine the combination of: a set of totalizer gears; a set of feelers adapted to coöperate *seriatim* with said gears; and means associated with said gears determining a differential motion of said feelers.

3. In an automatic total printing device; a totalizer; printing mechanism; automatic means to operate the same; and a set of feelers adapted to coöperate with said totalizer in all of its decimal places *seriatim* and thereby initiate the automatic operation of said printing device as determined by a particular one of said feelers.

4. In a calculating machine the combination of: a set of totalizer gears; a set of feelers adapted to coöperate with said totalizer gears *seriatim*; a set of digit keys; a set of latches associated with said digit keys; and means to automatically operate any of said latches upon displacement of the same.

5. In a calculating machine the combination of a set of displaceable elements which may be displaced to represent a number: a set of feelers adapted to coöperate with said displaceable elements *seriatim*; a set of digit keys; and means operating said digit keys *seriatim* in a sequence determined by the position of said displaceable elements.

6. In a calculating machine the combination of: printing mechanism; automatic means to operate the same; a set of displaceable elements adapted to represent a number by their displacement, said elements being arranged in groups; determining means coöperating *seriatim* with

said displaceable elements to determine the operation of said printing mechanism; and means rendering said printing mechanism inoperative when said determining means coöperates in a pointing off space.

7. In a calculating machine the combination of: an automatic total printing device; a source of power; and a slip clutch connecting said source of power and automatic total printing device.

8. In a calculating machine the combination of: an automatic total printing device; a source of power; a slip clutch connecting said source of power to said automatic total printing device; and means to lock said automatic total printing device upon the completion of its operation and thereby cause the slippage of said clutch.

9. In a calculating machine, the combination of a totalizer gear having a short tooth, a set of feelers adapted to be thrown into contact with said gear, a set of type bars, operating means for said type bars, and means associated with said set of feelers to determine the operation of the type bar selected by the contact of one of said feelers with said short tooth.

10. In a calculating machine, the combination of a set of totalizer gears each of which contains a short tooth, a set of feelers adapted to engage *seriatim* with said gears, a set of type bars, operating means for said type bars, and connections between said set of feelers and said type bars whereby said operating means operates a type bar as determined by the position of said short tooth on the totalizer gear engaged by said feelers.

11. In a calculating machine, the combination of totalizer gears, a set of feelers adapted to coöperate *seriatim* with said gears and a short tooth on some of said gears to determine the differential motion of said feelers.

12. In a calculating machine, the combination of a set of totalizer gears, a set of feelers adapted to coöperate *seriatim* with said gears, said feelers being normally out of engagement with said gears, a short tooth on some of said gears to determine a differential motion of said feelers, and means to automatically bring said feelers into contact with one of said gears and withdraw said feelers subsequent to the automatic determination by said feelers of the position of said short tooth.

13. In a calculating machine, the combination of a totalizer, a set of type bars, a latch associated with each of said type bars, common operating means for said type bars and a set of feelers to automatically determine the displacement of a latch corresponding to the position of a gear in said totalizer.

14. In a calculating machine, the combination of a totalizer, a set of type bars, each of said bars having a latch pivoted thereon, a common operating means for said type

bars, and a set of feelers to automatically determine the displacement of a latch corresponding to the position of a gear in said totalizer.

5 15. In a calculating machine, the combination of a totalizer, a set of type bars, each of said type bars having a latch pivoted thereon, an oscillating bar adapted to engage in said latches and thereby operate said type bars, and a set of feelers to automatically determine the displacement of a latch corresponding to the position of a gear in said totalizer into the path of said oscillating bar.

10 16. In a calculating machine, the combination of a totalizer, a set of type bars, each of said bars having a latch pivoted thereon, an oscillating bar adapted to engage said latches and thereby operate any of said type bars, a set of feelers coöperating with said 20 totalizer to automatically determine the displacement of a particular latch into the path of said oscillating bar, and means to bring said feelers into coöperation with said totalizer in each decimal place thereof *seriatim*.

25 17. In a calculating machine, the combination of a totalizer, a set of feelers, adapted to coöperate with said totalizer and pivoted in staggered arrangement, said feelers having the parts which contact with said totalizer brought into a single plane.

80 18. In a calculating machine, the combina-

tion of a set of feelers, a set of type bars, power-operating means for said type bars, a set of latches, each latch being pivoted to a type bar, a spring normally holding each latch out of the path of the operating means and a set of links connecting said feelers and said latches whereby a displacement of any of said feelers will throw its associated latch into the path of the operating means. 40

19. In a calculating machine, the combination of a totalizer, a set of feelers adapted to coöperate therewith, elastic means tending to bring said feelers into contact with said totalizer, and a universal bar adapted 45 to hold said feelers out of contact with said totalizer.

20. In a calculating machine, the combination of a totalizer, a set of feelers adapted to coöperate therewith, elastic means to bring said feelers into contact with said totalizer, a universal bar adapted to hold said feelers out of contact with said totalizer, and automatic means to operate said universal bar. 50

In witness whereof I have hereunto subscribed my name in presence of two witnesses.

JOHN BRICKEN.
